UNITED STATES PATENT OFFICE.

JOHN N. HOWE, OF FRANKLIN, NEW HAMPSHIRE.

IMPROVEMENT IN EXTINGUISHERS FOR LAMPS.

Specification forming part of Letters Patent No. **59,607**, dated November 13, 1866.

To all whom it may concern:

Be it known that I, JOHN N. HOWE, of Franklin, in the county of Merrimack and State of New Hampshire, have invented certain Improvements in Extinguishers for Lamps, of which the following is a full, clear, and exact description, reference being had to the accompanying drawings, making part of this specification, in which—

Figure 1 is a perspective view of a lamp-burner with my improved extinguisher applied thereto. Fig. 2 is a vertical section through the center of the same with the chimney and its cap in place.

My invention has for its object to provide a simple, convenient, and efficient means of extinguishing the light of lamps of various construction, whereby the necessity of removing the chimney and the danger of explosion heretofore occasioned (by blowing the flame in contact with and igniting the gases within the lamp) are avoided; and my invention consists in an open tube passing from the outside of the burner to the top or near the top of the wick-tube, a current of air being blown upward through the extinguishing-tube, which is so formed and placed as to direct and concentrate the air at the base of the flame when it is required to be extinguished.

To enable others skilled in the art to understand and use my invention, I will proceed to describe the manner in which I have carried it out.

In the said drawings, A represents the perforated casing of an ordinary kerosene-lamp burner. B is the cap which supports the chimney C, and D is the wick-tube.

Between the outside of the lower portion of the perforated casing and the upper edge of one side of the wick-tube (and inclined upward thereto) is placed a tube, E, the lower end, *a*, of which is of a circular form, while toward its upper end it becomes flattened and terminates in a narrow slit, *b*, extending across the whole length of the wick, as seen in section, Fig. 2.

When it is required to extinguish the flame of a lamp it is simply necessary to place the mouth near the orifice *a* and blow into the tube E, which is of such a form and so inclined to the wick that the current of air is concentrated at the slit *b*, and is so forcibly expelled therefrom as to instantly cut off or extinguish the flame with but little or no smoke, and thereby prevent any disagreeable odor arising therefrom.

The form and position of the tube E may be varied somewhat without departing from the spirit of my invention, and the said tube may project outside of the perforated casing or be provided with a mouth-piece, if desired; but the construction herein shown and described is what I prefer.

What I claim as my invention, and desire to secure by Letters Patent, as an improvement in extinguishers for lamps, is—

The tube E, through which a current of air may be directed to the flame, substantially as set forth.

JOHN N. HOWE.
